UNITED STATES PATENT OFFICE.

GEORGE FRANKLIN CUSHMAN, OF BARNET, VERMONT, ASSIGNOR TO HIMSELF, AND FRANCIS A. CUSHMAN, OF PLYMOUTH, NEW HAMPSHIRE.

BOOT OR SHOE.

SPECIFICATION forming part of Letters Patent No. 374,890, dated December 13, 1887.

Application filed October 5, 1885. Serial No. 178,988. (No model.)

To all whom it may concern:

Be it known that I, GEORGE FRANKLIN CUSHMAN, of Barnet, in the county of Caledonia and State of Vermont, have invented 5 certain new and useful Improvements in Boots or Shoes or Parts thereof, of which the following, taken in connection with the accompanying drawings, is a specification.

I have discovered that certain classes of 10 boots or shoes, and more generally the interior or protected parts of boots or shoes—such as inner soles, counters, box-toes, and heels, usually made of leather or leather-board—may with equal efficiency be formed 15 from a much cheaper material, (capable also of being molded into the form desired,) to wit, from the exceptionally strong and tough wood pulp produced by the chemical and mechanical treatment set forth in the Letters Patent 20 for "process of making wood pulp from wooden blocks," granted to me October 27, 1885. In said process the wooden blocks were first boiled in a solution which toughened while tending to separate their fibers, and were then 25 disintegrated by the action of a revolving grinder.

The product of that process or wood pulp 30 so made mixed with a portion of strong paper-stock, when run off comparatively thin and dried, is especially tough and tenacious, but may be cut and shaped by hand or machinery or molded to the desired form, and is therefore adapted, by its cheapness and its inherent qualities, for the production of various parts 35 of boots or shoes. Indeed, by some external application of water-proof material, or by mixing with the pulp some ingredient to repel moisture, the entire shoe may be made from the product referred to. Without such water- 40 proofing slippers and other house shoes can be made from this improved material, and are found to be light and durable.

The drawings illustrate some applications 45 of my invention, Figure 1 representing a shoe made entirely of wood pulp toughened as stated. Fig. 2 shows an inner sole; Fig. 3, a counter or heel stiffener; Fig. 4, a heel formed of this improved material; and Fig. 5 represents the shoe in vertical section, showing the 50 relation of the parts.

The shoe shown in Figs. 1 and 5 is made up of separate parts, molded to shape from toughened wood pulp, the sole, heel, and counter being quite thick and practically rigid, while the shank and upper are thin enough to yield 55 somewhat to the movements of the foot or to conform to its outlines.

The various parts of the shoe are formed 60 separately, of differing thicknesses of the material, shaped to the foot and suitably secured together. The uppers, being thinner and subject to peculiar strains, should be from the best of the material, and may have a liberal admixture of strong stock. This grade should also be selected for making the heel-stiffeners, 65 Fig. 3, unless they are molded quite thick or shaped from extra heavy blanks. The shaping will be effected by counter-machines of the usual construction. The inner soles, Fig. 2, and heels, Fig. 4, may, however, be formed 70 from the common or inferior grades. Such soles will be commonly cut by dies and shaped in a press or by hammering. Heels may either be molded solid or hollow or be built up of a succession of lifts of the sheeted pulp cemented or nailed together and subsequently 75 shaped by hand or machine work. Water-proofing may be resorted to, if desired.

I am aware of the common use of leather-board in the manufacture of heel-stiffeners, 80 and that such leather-board stiffeners have sometimes been coated with a water-proof composition. (See, for example, the patent of Moore, dated November 11, 1873.)

I am also aware of the patent to Hesse, dated 85 May 9, 1882, for "undershoe," wherein is described a low, seamless, paper-pulp sandal to go inside the stocking, such sandal being formed with an external re-enforce or cloth facing. I make no claim to such pulp-and- 90 cloth undershoe, nor to a shoe or any part thereof made of leather-board, my toughened pulp having inherent strength adequate to the requirements of boots or shoes without external fibrous re-enforcement, and my material 95 being in character and capabilities substantially unlike leather-board.

Parts of shoes having been made of paper, leather-board, &c., I do not claim such; but 100 What I claim is—

1. A shoe made of the toughened wood pulp herein described, and consisting of separate parts made from said material united to form a foot-covering, substantially as set forth.
- 5 2. A boot or shoe provided with an inner sole of the toughened wood pulp herein described, suitably secured, substantially as set forth.
- 10 3. A boot or shoe provided with a heel built up of successive layers of the toughened wood pulp herein described, and suitably secured to the shoe, substantially as set forth.

4. A boot or shoe provided with a heel-stiffener made of the toughened wood pulp herein described, suitably connected to the shoe, substantially as set forth. 15

In testimony whereof I have signed my name to this specification, in the presence of two subscribing witnesses, on this 19th day of September, A. D. 1885.

GEORGE FRANKLIN CUSHMAN.
